COMBINED ELECTRIC KNIFE CHARGER RACK AND BLADE HOLDER OR SIMILAR ARTICLE

John C. Shalvoy, Fairfield, and Max C. Hauenstein, Monroe, Conn., assignors to General Electric Company, a corporation of New York

Filed Oct. 13, 1964, Ser. No. 82,164

Term of patent 14 years

(Cl. D26—15)

FIG. 1 is a top perspective view of a combined electric knife charger rack and blade holder embodying the new design;

FIG. 2 is a front elevational view thereof;

FIG. 3 is a top plan view thereof;

FIG. 4 is a rear elevational view thereof; and

FIG. 5 is a side elevational view thereof.

We claim:

The ornamental design for a combined electric knife charger rack and blade holder or similar article, substantially as shown.
